UNITED STATES PATENT OFFICE.

EDWARD BATTERMAN, OF HOBART, INDIANA.

DISK-GRINDER.

1,213,727.

Specification of Letters Patent. Patented Jan. 23, 1917.

Application filed September 19, 1916. Serial No. 120,985.

To all whom it may concern:

Be it known that I, EDWARD BATTERMAN, a citizen of the United States, residing at Hobart, in the county of Lake and State of Indiana, have invented new and useful Improvements in Disk-Grinders, of which the following is a specification.

This invention relates to apparatus for grinding cultivator and other similar disks, the primary object of the invention being to provide a grinder which is simple of construction, reliable and efficient in action, susceptible of being manufactured and sold at a reasonable cost, and adapted to support disks of different sizes and thicknesses for the grinding action.

A further object of the invention is to provide a grinding apparatus embodying means for relatively adjusting the disk carrier or grinder head with relation to the grinder wheel, so as to vary the relationship of the parts according to the diameter and thickness of the disk, and the pitch or arrangement of the edge of the disk with respect to the grinding wheel, as well as to compensate for irregularities in the surface of the edge of the disk to obtain an even and efficient grinding action, and to provide for the rotation of the grinding wheel and disk at different relative speeds to regulate the grinding action as desired and prevent overheating of the disk.

A still further object of the invention is to provide a grinding apparatus embodying means for effecting the desired adjustments in a ready and convenient manner.

The invention consists of the features of construction, combination and arrangement of parts hereinafter fully described and claimed, reference being had to the accompanying drawings in which:—

Figure 1 is a side elevation of a disk grinding apparatus embodying my invention. Fig. 2 is a front elevation of the same. Fig. 3 is a top plan view. Fig. 4 is a vertical transverse section on line 4—4 of Fig. 3. Fig. 5 is a vertical transverse section on the line 5—5 of Fig. 3. Fig. 6 is a vertical longitudinal section on the line 6—6 of Fig. 3.

In carrying my invention into practice I provide a grinding apparatus including a main frame 1 and a grinder supporting frame 2, which frame 2 is provided at a point adjacent but in advance of its rear end

with a transverse rod or axle 3 journaled in bearing brackets 4, whereby said grinder frame is mounted to tilt vertically upon the main frame. At its forward end the grinder frame is provided with suitable bearings 5 for a transverse grinder shaft or arbor 6 on which is mounted a pulley 7 connected by a belt 8 with a drive pulley 9, whereby said shaft is driven. One end of the shaft or arbor 6 carries a grinding wheel 10, composed of emery or other suitable material, and provided with a hub or sleeve 11 adapted to be fitted upon the shaft and secured in position by a washer 12 and clamping nut 13. The shaft and wheel hub are squared or otherwise suitably connected to fix the wheel to the shaft for rotation therewith, the construction being such that grinding wheels of different sizes or kinds may be interchangeably used. The outer or opposite end 14 of the grinder shaft is extended and may be employed in practice to receive a buffing wheel or other appliance. The drive pulley 9 is fixed to a transverse drive shaft 15 which is provided with fast and loose pulleys 16 and 17 to receive a drive belt from a suitable source of power. The belt may be shifted from one pulley to the other by means of a sliding forked shifter 18 operated by a shifting lever 19 in an obvious manner. The frame 2 is pivotally mounted in close proximity to the drive shaft 15, so that the forward end of said frame may have a considerable degree of tilting motion, with a minimum degree of tilting motion of the rear end of said frame. The shaft 15 is mounted in bearings 20 suitably journaled and adjustably mounted upon the main frame 1 and adapted for adjustment by screws 21 carried by brackets 22, whereby said shaft may be adjusted with relation to the shaft 11 to take up any slack in the belt 8. The brackets 22 are reinforced from the main frame by suitable stays 23. On the shaft 15 is a worm 24 meshing with a gear 25 on a longitudinally extending transmission shaft 26, for transmitting motion to the disk carrier or supporting head 27.

The head 27 is detachably mounted upon the upper end of a vertical disk driving shaft 28, which is journaled at its upper end in a movable bearing member 29 and at its lower end in a movable bearing member 30. The upper end of said shaft is reduced to 110

receive the head 27 and is threaded to receive a clamping nut 31, whereby the disk 32 to be ground is clamped in position against the head, a coiled spring 33 being disposed between the nut and disk to yieldingly back the latter, thus allowing the disk to have a certain degree of yielding vertical play or motion to maintain it in contact with the grinding wheel, while compensating for any irregularities of surface on the disk to be reduced by the grinding action. The bearing 30 is carried by a swinging yoke 34 which is mounted to tilt upon a horizontal transverse transmission shaft 35 and carries a beveled gear 36 meshing with a gear 37 on said shaft, whereby the shaft 28 is driven. Fixed to the shaft 35 is a gear 38 having a plurality of concentrically arranged toothed portions any one of which may be engaged by a gear pinion 39 for driving said shaft and through it the grinder head to vary the speed of rotation of the disk being ground to suit any particular grinding action or to prevent the disk from being overheated. The gear 39 is slidably mounted upon an angular portion 40 of the shaft 36 and is connected with an adjusting lever 41 which slidably and pivotally engages a pivot bolt 42, the pinion being adjustable by means of said lever entirely out of engagement with the gear 38 or into engagement with any of its toothed faces in a manner readily understood. The lever is adapted to engage any one of a series of notches 43 in a locking plate 44 to maintain in any of its adjusted positions, and a spring 45 is provided upon the bolt 42 for coöperation with a retaining nut 46 whereby locking and releasing movements of the lever is permitted in a manner readily understood.

Carried by the main frame is a bracket 47 which supports an internally threaded bearing member or nut 48 through which extends and in which operates a threaded rod or screw 49 having at its outer end an actuating handle 50. The inner end of this screw, which is cylindrical and plain-surfaced, is telescopically connected with the bearing member 29, and inclosing said plain-surfaced cylindrical portion of the screw rod or shaft is a coiled spring 51 backed by an adjustable abutment or nut 52 whereby a yielding motion transmitting connection between the said bearing member 29 and the screw rod or shaft is afforded. From this it will be seen that by adjusting the screw rod or shaft, a grinder head carrying the disk may be adjusted toward and from the grinding wheel, to suit different diameters of disks, as well as to provide for the adjustment of the disk with relation to the surface of the grinding wheel to pitch or dispose the disk for the grinding of a proper baffle, it being understood that the spring connection permits the disk to vibrate back and forth,

while yieldingly holding it to its work, so that irregular and unusual hard surfaces may be compensated for and a gradual and uniform grinding action secured.

As shown, particularly in Fig. 6, the forward end of the grinder wheel frame is provided with a supporting plate or bracket 53 which slidably receives the upper end of a supporting rod 54 having its lower portion provided with spiral or worm threads, the lower end of said rod being journaled and slidably mounted in the frame 1 and extending through a bracket 56, between which bracket and the underlying portion of the frame is arranged an adjusting wheel 57 having a threaded hub engaging said shaft, whereby through reverse movements of said wheel the rod may be raised or lowered. Surrounding the rod between the bracket 53 and the bracket 56 is a coiled spring 58 which serves as the immediate support of the forward end of the frame 2, allowing said support to have vertical pivotal motion to adjust the grinding wheel up and down, and also adapt it to have yielding motion so that, through the yielding motions of the grinding wheel and disk undue harshness of action will be avoided and the grinding action evenly and smoothly effected. It will be observed that by raising and lowering the rod the tension of the spring will be varied to regulate the supporting and pressure actions accordingly.

In the operation of the device, the disk to be sharpened is fitted upon the threaded upper end of the shaft 28 and yieldingly secured in position by the clamping nut 31 and spring 33, this spring permitting the disk to have independent yielding motion for the purpose heretofore set forth. The grinder head and grinding wheel are then adjusted to properly dispose the edge of the disk with relation to the periphery of the wheel for a grinding action and the machine is then set in motion whereby the grinding wheel and disk will be simultaneously rotated in peripheral contact with each other, resulting in the grinding of the disk at the proper angle and to the proper degree.

It will of course be understood that by means of the adjusting members described the grinding pressure on the disk may be varied, while the disk and wheel are permitted to have independent relative yielding motions in various directions to adapt the stone to cut or smooth down the disk evenly and uniformly within a minimum period of time. Furthermore, the parts may be manually adjusted at intervals as the disk is ground and until the disk is ground to the desired degree.

It will be seen that the device admits of the grinding of disks of different diameters and different pitches or bevels of cutting

surfaces, as well as rotation of the disk at any one of a number of speeds desired without varying the speed of the grinding wheel, thus enabling the grinding action to be 5 thoroughly controlled.

By the use of the machine a cultivator and other like disk may be ground in a rapid, convenient and economical manner, as will be readily understood.

10 I claim:—

1. A disk grinding machine including a grinding shaft, a grinding wheel carried by the shaft, means for yieldingly supporting said shaft, a disk carrying shaft, means for 15 yieldingly supporting said shaft with relation to the grinder shaft, and means for yieldingly supporting the disk upon the disk carrying shaft.

2. A grinder machine including a main 20 frame, a vertically movable frame supported by the main frame, means for vertically adjusting and yieldingly supporting the vertically movable frame, a grinding shaft carried by the vertically movable frame, a 25 grinding wheel mounted upon said shaft, a vertical disk supporting shaft, and means for yieldingly supporting said shaft for

movement toward and from the grinding shaft.

3. A disk grinder machine including a 30 horizontal, vertically movable grinding shaft, means for adjustably and yieldably supporting said shaft, a grinding wheel carried by the shaft, a vertical shaft mounted for movement toward and from the 35 grinding wheel, a disk carrying support upon said vertical shaft, and means for adjusting and yieldably supporting the vertical shaft.

4. A disk grinding machine including 40 a horizontal vertically movable grinding shaft, means for adjustably and yieldably supporting said shaft, a grinding wheel upon the grinding shaft, a vertically disposed disk carrying shaft, means for sup- 45 porting a disk thereon for peripheral contact with the grinding wheel, an adjusting device engaging said vertical shaft for adjusting the same toward and from the disk grinding shaft, and means associated with 50 said adjusting shaft for yieldingly backing the vertical shaft.

In testimony whereof I affix my signature.

EDWARD BATTERMAN.
